CARTON

Joseph Gariepy, Everett, Mass., assignor to
United Drug Company, Boston, Mass., a corpo-
ration of Delaware

Application August 16, 1941, Serial No. 407,111

6 Claims. (Cl. 206—44)

This invention relates to an improved carton formed from cardboard or other suitable material.

Among the objects of this invention is the provision of a carton which may be used, not only as a container, but which may easily be converted for display purposes; and the provision of a carton which is formed of a one-piece blank with very little waste of material. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a layout of the improved carton blank;

Fig. 2 is a plan view of the carton in a subsequent folded position, a small portion being broken away;

Fig. 3 is a perspective view showing a later stage in the formation of the carton;

Fig. 4 is a perspective view showing a still later stage;

Fig. 5 is a perspective view showing the formed carton employed for display purposes;

Fig. 6 is a side elevation of the formed carton; and,

Fig. 7 is a view similar to Fig. 6, but showing the carton in a different position.

Similar reference characters indicate corresponding parts throughout the several views of the drawing.

The carton blank illustrated in Fig. 1 is formed of cardboard or other suitable material cut and scored substantially as shown. It comprises bottom portions 1, 2, 3 and 4 separated by cuts 40, 41 and 42, arranged in a line; side portions 5 and 6; end portions 7 and 8, and a pasting tab 9 on portion 5. Portions 5, 6, 7, 8 and 9 are arranged in a straight line which is parallel to the line of portions 1—4. The blank also comprises a top 10 with an attached fold portion or web 11, 47, 49 contiguous to the side 5 and end 7.

Tongues 12 and 13 are formed in one bottom portion for forming a closure with cuts 14 and 15. The side and end portions 5, 7, 6 and 8 are continuous and have suitable score lines between them. The bottom portions 1, 2, 3 and 4 are attached respectively to side 5, end 7, side 6 and end 8 by means of a score line 43. The top 10 is relieved from side 6 and end 8 by a cut 20, but is attached to folding flap 11, 47, which latter is attached to both end 7 and side 5 by the brace

49 and score lines 45 and 53 respectively. Score lines are otherwise formed substantially as shown.

Top 10 is divided into two sections along a cut 16 and fold lines 17 and 18. Folding portion 11 is hinged along the cut 21, and score lines 22 and 23. Cut 21 provides an attaching tab 24. As stated, brace 49 is divided from parts 47 and 5 by score lines 51 and 53 respectively, and thus may angle as desired and as will appear.

Fig. 2 illustrates the blank of Fig. 1 folded along score lines 25 and 26 with tab 9 pasted under the front end 8. The blank in this condition is ready for assembly to form a completed box, as shown progressively by Figs. 3, 4 and 5, without the necessity for further pasting or other attaching operations. After folding up of portions 2, 4, 3 and 1, in order, insertion of tongues 12 and 13 into slits 14 and 15 forms the bottom. Folding in of the portion 11, as shown in Figs. 3 and 4, while angling said portion or web 11, 47, and brace 49 along lines 44, 21, 22, 23, 51 and 53 finally forms the carton. The score line 44 is moved next to score line 45, as indicated by the arrow in Fig. 4 (see also Fig. 7). Where additional rigidity is desired, the tab 24 may be pasted to the back 7.

The top 10 is utilized in the position shown in Fig. 4 (that is, not folded along the score lines 17 and 18) when the device is used for transporting articles or for general use as a container. The top, when utilized thus, is shown in Fig. 7 and in dotted lines in Fig. 6.

When use for display purposes is desired, the top portion 29 is merely bent along fold lines 17 and 18 so that the rounded portion 27 projects upward from the plane of part 29. The flap 28 is at this time straightened out so as also to be parallel with the portion 29 and is placed against the inside of the rear portion 7. The box therefore assumes the Fig. 5 position. Thus it will be seen that the top 10 is breakable or collapsible at 16, 17, 18 to bend down part 29.

The blank for forming the carton described above may be formed economically from cardboard or other stock and only a very small proportion of cardboard is lost in the cutting operation. This is partly because the top 10 lies parallel to the side 6. There are substantially no wasteful projecting parts. The result is a decreased cost of manufacture. Moreover, the box may be folded and pasted to the Fig. 2 position and large numbers may be transported flat to the user. A large number of carton blanks can be transported or stored in the Fig. 2 condition flat, and easily assembled when desired for use as containers. The user can then easily assemble as a box, without any cutting or pasting operations, if desired.

Any suitable advertising or descriptive matter may be printed on the top, sides and ends of

the box carton. The portion of the top 10 which is below the cut 16, namely, projecting portion 27 and the portion 29 therebelow, will carry the advertising matter which it is desired to display prominently when the box is open (Fig. 5).

The end portion 8 which forms the front of the box is preferably formed with a recess 30 cut therein which permits easy removal of the flap 28 where the flap is inserted inside the front end 8. In addition, it aids in the easy removal of the articles contained therein.

The triangular portion or web 49 which joins part 47 to part 5 at score lines 51 and 53 being turned down in proceeding from the positions between Figs. 3 and 4, serves, particularly in the display position of Fig. 5, to hold the part 47 against the back 7. As above stated, the additional pasting of the tongue 24 to said back 7 may be employed after the parts are folded up as a box, but this is not absolutely necessary.

Recapitulating, the invention consists in portions or panels cut and scored to form a box open at the top, wherein the back end has an extension horizontally hinged thereto, said extension including a breakable or collapsible top perpendicularly hinged thereto, with an angular hinge in the extension intersecting or meeting the junction of the horizontal and perpendicular hinges to permit of the extension being turned down against the back while the perpendicular hinge moves adjacent to the horizontal hinge; whereby when the top is opened and set to collapsed position it forms a display from the back of the open box. In addition, there is a brace hinged between the extension and one side of the box which acts to hold the extension against the back after assembly.

Advertising matter carried upon the portion 29 of the top 10 is readable from the front of the box either in its box-closed position or its box-open position. For convenience in the drawing, the advertising matter is indicated by the characters A, B, C.

In view of the above, it will be seen that the several objects of the invention are achieved and other advantageous results attained.

As many changes could be made in the above constructions without departing from the scope of the invention, it is intended that all matter contained in the above description or shown in the accompanying drawing, shall be interpreted as illustrative and not in a limiting sense.

I claim:

1. In a folding box formed of side, end, and bottom portions cut and hinged to form a box open at the top, an extension from one of said ends hinged thereto, a top joined to said hinged extension and hinged thereto perpendicularly to said extension hinge, an angular score line in said extension arranged to meet the junction of said hinges to allow movement of said perpendicular score line against the top edge of said end, said top being provided with means for angling one portion back against another portion when the top is open thereby to form an upright display.

2. In a folding box formed from a one-piece blank cut and scored to form side, end, and bottom portions to form a box open at the top, an extension from one of said ends hinged horizontally, a triangular web joining the extension and one side, a top hinged to said hinged extension

perpendicularly to said horizontal hinge, an angular score line in said extension arranged to meet the junction of said hinges to allow of bringing said perpendicular score line against the horizontal score line, said top being provided with means for angling one portion back against another portion when the top is open thereby to form a display, said web holding said another portion of said top against the back of the box.

5 3. In a folding box formed from a one-piece blank cut and scored to form side, end, and bottom portions to form a box open at the top, an extension from one of said ends hinged horizontally, a triangular web joining the extension and one side, a top hinged to said hinged extension perpendicularly to said horizontal hinge, an angular score line in said extension arranged to meet the junction of said hinges to allow of bringing said perpendicular score line against the horizontal score line, said top being provided with means for angling one portion back against another portion when the top is open thereby to form a display, said web holding said another portion of said top against the back of the box,

15 20 and a tongue extending from said angular score line for attachment to the adjacent box end.

25 4. In a folding box formed from a one-piece blank, side, front end, back end, and bottom portions cut and scored to form a box open at the top, an extension hinged horizontally on the top of said back end for angling down against the inside of said back end, a web joining the extension and one side by score lines permitting said angling down of the extension, said web acting as a brace holding the extension in place after assembly, a top forming an extension from said hinged extension and hinged thereto vertically, an angular score line in said extension joining the vertical and horizontal hinges where they cross and arranged to allow of bringing said vertical score line against the top edge of said end, said top being provided with means for angling one portion back against another portion when the top is opened thereby to form a vertical display in the plane of said back end.

30 45 5. An article of manufacture comprising a one-piece blank cut and scored for folding to form a box open at the top having an end, an extension hinged to said end by a horizontal score line, said extension including a top hinged thereto on a score line normal to the horizontal score line whereby top material is located adjacently to side material in the blank, and an angular score line in the extension intersecting the junction of said hinges and permitting of its being turned down against said end to permit movement of the normal score line against the horizontal score line.

55 60 6. An article of manufacture comprising a one-piece blank cut and scored for folding to form a box open at the top having an end, an extension horizontally hinged to said end by a score line, said extension including a top perpendicularly hinged thereto on a score line intersecting said horizontal score line, whereby top material is located adjacently to side material in the blank, and an angular score line in the extension intersecting the junction of said hinges and permitting of its being turned down against said end to permit movement of the extension against the inside of said end.

65 70 JOSEPH GARIEPY.
